UNITED STATES PATENT OFFICE.

ORWELL H. NEEDHAM, OF NEW YORK, N. Y., ASSIGNOR TO ELIAS P. NEEDHAM AND CHARLES A. NEEDHAM, OF SAME PLACE.

SOUND-BOARD FOR MUSICAL INSTRUMENTS.

SPECIFICATION forming part of Letters Patent No. 274,813, dated March 27, 1883.

Application filed July 14, 1882. (No model.)

To all whom it may concern:

Be it known that I, ORWELL H. NEEDHAM, of the city and county of New York, in the State of New York, have invented a certain 5 new and useful Improvement in Sound-Boards for Musical Instruments, of which the following is a specification.

My invention relates more particularly to pianos and organs; but it may be embodied in 10 other musical instruments; and the object of my invention is to amplify and augment the sound-waves issuing from such instruments, and thus increase their power.

The invention consists in the combination, 15 in a musical instrument, with a solid sound-board, of two or more hollow sound-boards made separate therefrom, and provided with openings or passages through which they communicate with each other, and each having a 20 bearing on said solid sound-board independently of and within the lines of the supports of said solid sound-board. The said hollow sound-boards preferably all communicate with a trunk or channel extending transversely to 25 them, and through which they all communicate with each other.

The invention also consists in the combination, with two or more hollow sound-boards, of devices for applying tension to each of said 30 sound-boards separately to slightly elongate or contract it, whereby provision is afforded for keeping them all at a uniform pitch.

The invention also consists in the combination of two or more hollow sound-boards provided with openings or passages through which 35 they communicate with each other, and also provided with smaller openings through which they each communicate with the atmosphere.

The invention also consists in the combination, 40 in a musical instrument, of a solid sound-board, two or more hollow sound-boards, each having a bearing on said solid sound-board, and provided with openings or passages through which they communicate with each 45 other, and with smaller openings through which each hollow sound-board communicates with the atmosphere, and devices for elongating or contracting each hollow sound-board to adapt them for producing sound-waves of uniform pitch.

In the accompanying drawings, Figure 1 represents a sectional elevation of a solid sound-board, three hollow sound-boards combined therewith according to my invention, and a supporting-frame. Fig. 2 represents an 55 inverted plan thereof. Fig. 3 represents a sectional elevation on the dotted line *x x*, Fig. 1. Fig. 4 represents a plan of three hollow sound-boards of a modified form, the solid sound-board being omitted; and Fig. 5 represents a 60 section upon the dotted line *y y*, Fig. 4, including the solid sound-board.

Similar letters of reference designate corresponding parts in all the figures.

A designates a solid sound-board such as is 65 usually employed in a piano, organ, or other musical instrument, and which is provided with ribs *a* upon the under side.

B designates a frame which supports the solid sound-board A, and which may be of any 70 form suitable for the instrument wherein it is to be used.

C designates hollow sound-boards, which are here shown as three in number; but one, two, or more than three sound-boards may be 75 employed, and if two or more are used they may be considered as forming a multiple sound-board of which each board is a section.

D designates a trunk or channel secured to the under side of and transversely to the 80 sound-boards C, and this trunk is represented as secured to the frame B, so as to support all the hollow sound-boards. The trunk or channel forms a passage extending across all the hollow sound-boards, and communicating with 85 each sound-board by means of an opening, *b*; hence it will be seen that through this passage and the opening *b* each sound-board C is in communication with all the others, so that sound-waves may flow from one to the other. 90 In each hollow sound-board, in this instance in its bottom, is an opening, *c*, through which it communicates with the atmosphere, and it will be observed that the said openings are smaller than the openings *b*, so that sound-waves will flow more readily from one to the other of the sound-boards than from each to the atmosphere. Each of the hollow sound-boards, although made separate from the solid sound-board, has a bearing upon the un- 95 roo

der side thereof, independently of and within the lines of the supports of said solid sound-board.

In the example of my invention shown in Figs. 1, 2, and 3 each sound-board has a pin, *d*, screwed into a hub or boss, *e*, thereon, so that it may be readily adjusted to project more or less from the hollow sound-board, and by adjusting these pins they may all be made to 10 press against the solid sound-board with equal pressure and maintained in such positions.

In the example of my invention shown in Figs. 4 and 5 each of the pins *d* is screwed into an arm, *f*, near one end, while the arm is 15 attached at its other end to the sound-board, a block or piece, *g*, being interposed between the board and arm to raise the latter out of direct contact with the sound-board, so that the end of the arm to which the pin *d* is attached 20 will be free to vibrate.

The arm *f* of the middle one of the three sound-boards extends parallel therewith; but the arms of the two outer sound-boards converge, as shown in Fig. 4.

25 In order to place the sound-boards *C* under tension, so as to keep them all at a uniform pitch, I provide means for slightly elongating or contracting them separately. The means here shown for the purpose consists of rods *h*, 30 one of which extends longitudinally through each sound-board. Each of these rods is screw-threaded at one end and engages with a nut, *i*, in one end of the sound-board, and the other end of the rod is held against longitudinal 35 movement by a collar, *j*, on the rod bearing against the inner side of the sound-board, and a head, *k*, bearing against the outside of the sound-board. The rod may be turned by means of the head *k*, and the sound-board is slightly 40 elongated or contracted, according to whether the rod is turned in one direction or the other. The rods *h* may be adjusted from time to time, as may be necessary, to keep the sound-boards in uniform pitch.

45 What I claim as my invention, and desire to secure by Letters Patent, is—

1. The combination, in a musical instrument, with a solid sound-board, of two or more hollow sound-boards made separate therefrom, provided with openings or passages through 50 which they communicate with each other, and each having a bearing upon the said solid sound-board independently of and within the lines of the supports of said solid sound-board, substantially as specified. 55

2. The combination, in a musical instrument, with a solid sound-board, of two or more hollow sound-boards, each having a bearing on said solid sound-board, and a trunk or channel arranged transversely to the hollow sound- 60 boards, with which they all communicate, and through which they communicate with each other, substantially as specified.

3. The combination, in a musical instrument, of two or more hollow sound-boards, and devices for applying tension to each of said sound-boards to slightly elongate or contract them, 65 whereby provision is afforded for making them all of uniform pitch, substantially as specified.

4. The combination, in a musical instrument, 70 of two or more hollow sound-boards provided with openings or passages through which they communicate with each other, and also provided with smaller openings through which they each communicate with the atmosphere, 75 substantially as specified.

5. The combination, in a musical instrument, of a solid sound-board, two or more hollow sound-boards, each having a bearing on the solid sound-board, and provided with openings 80 or passages through which they communicate with each other, and with smaller openings through which each hollow sound-board communicates with the atmosphere, and devices for elongating or contracting each hollow sound- 85 board to adapt them for producing sound-waves of uniform pitch, substantially as specified.

O. H. NEEDHAM.
